UNITED STATES PATENT OFFICE.

EDWARD M. HEWLETT, OF SCHENECTADY, NEW YORK, ASSIGNOR TO
GENERAL ELECTRIC COMPANY, A CORPORATION OF NEW YORK.

REVERSE-CURRENT RELAY.

No. 818,377.

Specification of Letters Patent.

Patented April 17, 1906.

Application filed October 22, 1904. Serial No. 229,546.

To all whom it may concern:

Be it known that I, EDWARD M. HEWLETT, a citizen of the United States, residing at Schenectady, in the county of Schenectady and State of New York, have invented certain new and useful Improvements in Reverse-Current Relays, of which the following is a specification.

My invention relates to reverse-current relays; and its object is to provide a novel, compact, and efficient structure for relays of this type.

Reverse-current relays having two movable windings, one energized from the current in the circuit to be protected and the other energized from a circuit in which current does not reverse with a reversal of current-flow in the first circuit, are well known in the art. A common form of relay consists in a small electric motor of the commutator type, the field or the armature being energized from the circuit to be protected and the other member of the motor being energized from a source which does not reverse. Thus it may be connected in shunt to the circuit to be protected or energized from an independent source, such as a battery or other independent circuit.

My invention consists in the novel form of connection between the movable armature and the relay-contacts controlled thereby.

My invention will best be understood by reference to the accompanying drawings, in which—

Figure 1 shows a side elevation of a relay constructed in accordance with my invention, and Fig. 2 shows a front elevation of the same.

In the drawings, A A represent bus-bars, generator-leads, or other conductors to be protected.

B represents the field structure of the relay, which consists simply of a magnetic member supported close to and partially surrounding the conductors A A. This member B is provided with field-poles b b, which are made detachable in order to enable the member B to be slipped into position around the conductors. This construction of the field-magnet member is similar to that disclosed in a former patent, No. 730,371, issued to me June 9, 1903. Between the field-poles b b is suspended the movable armature C. (Shown in dotted lines in both figures.) This armature

has a vertical shaft which is supported in 55 bearings in the two protecting-caps D D', which are made of non-magnetic material and which are supported from the field-poles b b and completely inclose and protect the armature C. The armature is provided with 60 the commutator-brushes O O, (shown in Fig. 1,) which are provided with terminals o o, supported outside the upper cap D. The lower cap D' is provided with a set-screw P, forming a bearing for the lower end of 65 the armature-shaft and affording convenient means for adjusting the position of the armature.

F represents a spiral spring surrounding the lower end of the armature-shaft and normally holding a pin g on the upper end of the armature-shaft in engagement with a stop d on the upper inclosing cap D.

The upper end of the armature-shaft carries a cam H, on which rides a roller I, supported from a pivoted lever i, as shown in Fig. 2. This lever guides the roller and receives the lateral pressure due to the inclined surface of the cam. The roller I carries a spindle J, the upper end of which extends 80 into a dash-pot or other suitable retarding device K. The spindle J carries near its center the bridging member L, which when the spindle J is raised by the rotation of the armature C and cam H bridges the contacts 85 M M, which are provided with suitable terminals m m for connection in the tripping circuit.

Adjustably secured to the pole-pieces b b is a magnetic member E, which acts as a 90 magnetic shunt for the armature. This magnetic member is separated from the pole-pieces by an air-gap or by strips of non-magnetic material e, as shown in Fig. 1. By means of the supporting-screws e' the distance between the member E and pole-pieces b b may be varied so as to vary the effective reluctance of the magnetic shunt. By this means the torque of the armature is readily 95 adjusted. The retarding device K and the stationary contacts M M are supported from the posts N N, which are secured to the pole-pieces b b. With this structure the relay is made compact and self-contained.

The operation of the relay will be evident 105 from the foregoing description. The armature is normally held by the spring F in the position shown, with the pin g in engagement

with the stop *d*. When the flow of current through the conductors *A A* is in the normal direction, the torque of the relay assists the spring tension in holding the armature against the stop. When the current reverses, however the torque of the relay will be reversed in direction and will oppose the spring tension. With a reverse current-flow of a predetermined amount the armature will be rotated away from the stop, rotating cam *H*, so as to cause roller *I* to raise spindle *J* to bring the bridging member *L* in engagement with the contacts *M M* and to close the tripping-circuit. The amount of reverse current-flow upon which the relay operates may be adjusted not only by varying the tension of spring *F*, but by adjusting the position of the magnetic shunt *E* relative to the pole-pieces *b b*, as has been heretofore explained.

20 I do not desire to limit myself to the particular construction and arrangement of parts here shown, but aim in the appended claims to cover all modifications which are within the scope of my invention.

25 What I claim as new, and desire to secure by Letters Patent of the United States, is—

1. In a relay, a stationary field-magnet member, an armature journaled between the poles thereof, a cam carried by the armature-shaft, a reciprocating member adapted to be moved by said cam, and a switch-contact carried by said reciprocating member.
2. In a relay, a stationary field-magnet member, an armature journaled between the poles thereof, a cam carried by the armature-shaft, a roller bearing on said cam, a longitudinally-movable spindle carried by said roller, and a switch-contact carried by said spindle.
3. In a relay, a stationary field-magnet member, an armature with a vertical shaft journaled between the poles of the field member, a cam at the upper end of said shaft, a roller bearing on said cam, a vertically-movable spindle supported by said roller, and a switch-contact carried by said spindle.
4. In a relay, a stationary field-magnet member, an armature with a vertical shaft journaled between the poles of the field member, a cam carried at the upper end of said shaft, a roller bearing on said cam, a vertically-movable spindle supported by said roller, a pivoted lever guiding said roller and

receiving the lateral pressure thereof, and a switch-contact carried by said spindle.

5. In a relay, a stationary field-magnet member, an armature journaled between the poles thereof, a cam carried by the armature-shaft, a reciprocating member adapted to be moved by said cam, a switch-contact carried by said reciprocating member, and means for retarding the movement of said reciprocating member.

6. In a relay, a stationary field-magnet member, an armature with a vertical shaft journaled between the poles of the field member, a cam carried at the upper end of said shaft, a roller bearing on said cam, a vertically-movable spindle supported by said roller, a switch-contact carried by said spindle, and means for retarding the movement of said spindle.

7. In a relay, a stationary field-magnet member, an armature journaled between the poles thereof, a cam carried by the armature-shaft, a reciprocating member adapted to be moved by said cam, a switch-contact carried by said reciprocating member, and means normally opposing the movement of said armature.

8. In a relay, a stationary field-magnet member, an armature with a vertical shaft journaled between the poles of the field member, a cam carried at the upper end of said shaft, a roller bearing on said cam, a vertically-movable spindle supported by said roller, a switch-contact carried by said spindle, and means normally opposing the movement of said armature.

9. In a relay, a stationary field-magnet member, an armature journaled between the poles thereof, a stop adapted to be engaged by the armature, a spring arranged to hold said armature normally in engagement with said stop, a cam carried by the armature-shaft, a reciprocating member adapted to be moved by said cam, and a switch-contact carried by said member.

In witness whereof I have hereunto set my hand this 20th day of October, 1904.

EDWARD M. HEWLETT.
